FASTENER-APPLYING IMPLEMENT

Arthur H. Maynard, Warwick, R. I., assignor to
Boston Wire Stitcher Company, Warwick, R. I.,
a corporation of Maine

Application January 4, 1939, Serial No. 249,183

11 Claims. (Cl. 1—3)

The present application is a continuation in part of my copending application for Fastener-applying implements, Serial No. 245,105 filed December 12, 1938.

5 One of the objects of the present invention is to provide a device of the type indicated having a base and a fastener-applying arm pivotally mounted thereon with the arm and base relatively adjustable to align the fastener-applying means on the arm with one or the other of 10 separate sets of clinching means on the base whereby to adapt the implement for clinching the fasteners by different methods.

Another object of the invention is to provide 15 a device of the type indicated having a single spring operative to yieldingly hold the fastener-applying arm raised with respect to the base, the fastener-applying means raised with respect to the arm and the arm biased to retain the pivot-pin carried thereby seated in one or the 20 other of separate sets of aligned notches in stanchions on the base.

Another object of the invention is to provide 25 a device of the type indicated having cooperating means on the fastener-applying arm and base for positively holding the pivot-pin in one or the other of the pairs of aligned notches in the stanchions on the base during operation of 30 the implement to prevent accidental displacement thereof.

Another object of the invention is to provide 35 a device of the type indicated having means on the base and fastener-applying arm operable as the latter is swung back from the base to cam the pivot-pin carried by the arm downwardly and rearwardly with respect to the base to automatically displace it from one pair of aligned notches and seat it in the other pair of aligned notches.

40 Still another object of the invention is to provide an implement of the type indicated of extremely simple and compact construction to adapt it for economical manufacture.

45 Further objects of the invention are set forth in the following specification which describes a preferred form of construction of the invention, by way of example only, as illustrated by the accompanying drawings. In the drawings:

50 Fig. 1 is a side view partly in section of a fastener-applying implement incorporating the present invention and showing the device adjusted to clinch the fasteners to form a permanent stitch;

55 Fig. 2 is a view similar to Fig. 1 showing the

implement adjusted to clinch the fasteners to form a temporary stitch;

Fig. 3 is a fragmentary perspective view of certain parts of the implement shown in disassembled relationship and illustrating the means for pivotally mounting the fastener-applying arm on the base to effect relative adjustment therebetween;

Fig. 4 is a longitudinal sectional view of the rearward end of the implement showing the cooperating means on the fastener-applying arm and base for positively holding the pivot-pin seated in one of the sets of aligned notches in the stanchions on the base;

Fig. 5 is a transverse sectional view taken on line 5—5 of Fig. 4 showing the contiguous relationship of the cooperating means on the fastener-applying arm and base for positively holding the pivot-pin seated in the aligned notches;

Fig. 6 is a transverse sectional view on line 6—6 of Fig. 1 illustrating the relationship of the parts at the completion of a fastener-applying operation and showing the legs of a driven fastener clinched to form a permanent stitch;

Fig. 7 is a transverse sectional view on line 7—7 of Fig. 2 showing the legs of the fastener clinched to form a temporary stitch;

Fig. 8 is a part-sectional view of the rearward portion of the implement showing the fastener-applying arm rocked away from the base to adapt the arm to be longitudinally adjusted with respect to the base;

Fig. 9 is a view similar to Fig. 8 showing the means on the base engaged by the rearward end of the fastener-applying arm to automatically adjust the latter from one to the other of its two positions during extreme swinging movement of the arm away from the base;

Fig. 10 is a view similar to Fig. 9 showing the relationship of the parts as the fastener-applying arm approaches alignment with the base during their relative swinging movement;

Fig. 11 is a side view of the implement shown partly in section with the arm and base swung into aligned relationship to adapt the implement 45 for use as a tacker; and

Fig. 12 is a part sectional view of the rearward portion of the implement showing the operating lever rocked away from the magazine to open the latter to receive a supply of fasteners and indicating in dotted lines the limit of its movement when the pivot-pin is seated in the forward notches and by dash lines the limit of its movement when the pivot-pin is seated in the rearward notches.

In the accompanying drawings the invention is illustrated as applied to a device for driving and clinching U-shaped staples but it is to be understood that the implement may be adapted 5 for applying other forms of fasteners. As herein illustrated the implement comprises a rectangular base 2 having a raised boss or anvil 3 at its forward end with separate sets of clincher-grooves 4 and 5 formed therein in spaced apart relationship. The clincher-grooves 4 are adapted to deflect the legs of a staple inwardly toward each other to form a permanent stitch as illustrated in Fig. 6; while the clincher-grooves 5 are adapted to deflect the legs of the staple outwardly 10 away from each other to form a temporary or pin-stitch as shown in Fig. 7. At the end of the base 2 opposite from the boss 3 are spaced stanchions 6, see Fig. 3, having rearwardly-projecting ears 7. The forward edge of one of the stanchions 6 is provided with a rearwardly-inclined cam-face 15 and below the cam-face the stanchion is recessed to provide a latching shoulder 16.

In accordance with the present invention the 25 rearwardly-extending ears 7 on the stanchions 6 of the base 2 are punched or pierced to provide slots 8 for mounting a pivot-pin 9 having an annular recess 10 in its periphery intermediate its ends. As shown most clearly in Figs. 3 and 8, 30 the slots 8 are of arcuate form to provide aligned pairs of notches 11 and 12 at their upper edges in which the pin 9 is adapted to seat, the notches 11 and 12 being spaced apart a distance equal to the distance between the separate sets of clincher-grooves 4 and 5 on the base 2. Below the 35 rearwardly-extending ears 7 a lug 17 is folded upwardly from the base 2 between the spaced stanchions 6 and then bent rearwardly to provide a flat ledge 18 with a shoulder or abutment 19 at its rearward end. The rearward edges of the stanchions 6 below the ears 7 are also formed to serve as abutments or shoulders 20 for a purpose as will be explained later. Preferably, the 40 base 2 is constructed in one piece blanked from sheet-metal stock with the boss 3 struck up therefrom and the clincher-grooves 4 and 5 stamped therein; while the stanchions 6 with the slots 8 pierced therethrough are folded upwardly at the sides of the base.

The fastener-applying arm 25 is similar to that 45 illustrated and described in my copending application, Serial No. 245,105, referred to above, and comprises a staple-magazine 26 and an operating lever 27 constituted as a cover in which the magazine is adapted to be nested. The parts 26 and 27 of the arm 25 are both hingedly mounted on the pivot-pin 9 for movement relatively of each other or together as a unit. Suffice it to state herein that the magazine 26 is of channel 50 shape in cross-section having a bottom wall 28 and upwardly-extending side walls 29 adapted to closely fit between the spaced stanchions 6 on the base 2. The side walls 29 of the magazine 26 are pierced adjacent their rearward ends with aligned holes adapted to receive the pivot-pin 9. At the forward end of the magazine 26 the bottom wall 28 is slotted rearwardly adjacent the opposite side walls 29 and the portion between 55 the slits is folded upwardly to form a shear-plate 30; while the projecting ends of the side walls 29 are folded inwardly in spaced relation to the shear-plate 30 to form a throat or guideway 31 for the staples. Intermediate the ends of the 60 magazine 26 a lug or projection is struck out-

wardly from one of the side walls 29 to provide a latching shoulder 32.

Extending longitudinally of the channel-shaped magazine 26 is a strut which may take the form of a rod 40 having its forward end bearing 5 against the rearward face of the shear-plate 30 and its opposite end engaging the pivot-pin 9. As illustrated most clearly in Fig. 4, the rearward end of the rod 40 projects through a hole in the upright portion of a right-angular bracket 41 10 and seats in the annular recess 10 in the pivot-pin 9. The horizontal portion 42 of the bracket 41 underlies the pivot-pin 9 to hold the end of the rod against upward displacement. Thus, the strut or rod 40 serves to brace the shear-plate 30 against displacement rearwardly and to retain the pivot-pin 9 in place.

The operating lever or cover 27 is of channel-shape arranged in inverted relation to the magazine 26 and having a top wall 43 and depending 20 side walls 44. The lever 27 is slightly wider and longer than the magazine 26 so that the top wall 43 projects beyond the forward end of the magazine and its side walls 44 overlie the sides thereof and the sides of the stanchions 6 on the base 25 2. The side walls 44 of the lever 27 are pierced adjacent their rearward ends with aligned holes adapted to receive the laterally-projecting ends of the pivot-pin 9.

A staple-driver 45 is attached to the top wall 30 43 of the lever 27 to adapt it to reciprocate in the throat 31 of the magazine 26 as the lever is rocked toward and away from the latter. As herein illustrated the driver 45 is formed by the forward narrowed portion of a sheet-metal angular plate 46 underlying the bottom side of the top wall 43 of the lever 27 and fitting closely between the side walls 44 to hold it against twisting movement. The angular plate 46 may be attached to the top wall 43 of the lever 27 by 40 a rivet 47 or any other suitable means such as welding.

A leaf-spring 48 has one end positioned between the angular plate 46 and the top wall 43 of the lever 27 and is connected to the latter by 45 the rivet 47 or other suitable means. The leaf-spring 48 is of a width equal to the distance between the side walls 44 of the lever 27 and extends throughout a substantial portion of the length of the lever, being generally curved arcu- 50 ately from its point of attachment to its free end as illustrated in Fig. 1.

A latch 55 is mounted to slide on the side wall 44 of the lever 27 adjacent that side wall 29 of the magazine 26 which is provided with the 55 latching shoulder 32. The latch 55 is in the form of a plate adapted to bear against the inside face of the side wall 44 and having ears 56 and 57 forming shoulders projecting from its opposite ends for cooperation respectively with the shoulder 32 on the magazine 26 and shoulder 16 on the stanchion 6 of the base 2, as explained more fully in my copending application referred to above. The rearward edge 58 of the latch 55 adjacent the ear 57 is inclined upwardly for 60 cooperation with the cam-face 15 on the stanchion 6 of the base 2 to adapt it to automatically slide the latch forwardly during the movement of the lever 27 to close the open side of the magazine 26. The ear 56 at the forward end 70 of the latch 55 normally underlies the latching shoulder 32 on the side wall 29 of the magazine 26 as illustrated in Fig. 1, but the latch may be slid rearwardly to release it from the shoulder 32 to engage the rearward ear 57 with the latch- 75

ing shoulder 18 on the stanchion 6 of the base 2. The latch 55 is retained on the side wall 44 of the lever 27 by means of a shank which projects outwardly through a slot or opening in the 5 wall and a finger-piece 58 which overlies the wall at the ends of the opening therein. The lever 27 is yieldingly held in raised position with respect to the base 2 by the engagement of the end of the spring 48 with the top edges of the 10 stanchions 6 and the magazine being connected to the lever 27 by the engagement of the ear 56 on the latch 55 with the shoulder 32 on the magazine is also held in raised position by the spring.

15 Staples s are supplied to the channel-shaped magazine 26 through its open top when the lever 27 is swung about the pivot-pin 9 to either position indicated by dotted or dash lines in Fig. 12. The crowns of the staples s extend laterally across 20 the interior of the magazine 26 which is so dimensioned that the opposite legs of the staple abut the inner faces of its side walls; the staples being supported in the magazine by the engagement of the ends of their legs with the bottom wall 28 thereof. The staples are advanced in the magazine by a pusher 65 mounted to slide on the rod or strut 40 and having forwardly-extending rails 66 engageable with the legs of the rearmost staple in 25 the series. The pusher 65 is urged forwardly by means of a compression spring 67 coiled about the rod 40 and acting between the angular bracket 41 and the rear of the pusher. The construction of the fastener-applying or stapling arm 25 as thus far described is substantially identical with that 30 illustrated in my prior copending application referred to above.

In accordance with the present invention the spring 48 performs an additional function in biasing the arm 25 to maintain the pivot-pin 9 seated in one or the other of the pairs of alined notches 45 11 and 12 in the stanchions 6 on the base 2. Due to the center of weight of the arm being located forwardly of the point of engagement of the end of the spring 48 with the stanchions 6 the arm tends to rock about the end of the spring as a pivot to hold the pivot-pin 9 seated in the appropriate pair of notches 11 or 12. However, to prevent accidental displacement of the pivot-pin 9 from the alined notches 11 or 12 in which it is seated during use of the implement, means are provided on the stapling arm 25 for cooperation with the lug 17 on the base 2 to positively hold the pivot-pin seated in the alined notches. As illustrated in Figs. 3 and 4 of the drawings, the bottom wall 28 of the magazine 26 is cut away at its rearward end to provide an opening 69 and forwardly of the opening the bottom wall is slotted at opposite points and the portion between the slits bent to provide a depending inclined lug 70. The lug 70 is so proportioned that its lowermost edge 71 is positioned directly below the center of the pivot-pin 9 and spaced from the ledge 18 on the lug 17 of the base 2 by only a few thousandths of an inch when the pivot-pin 9 is seated in one 55 or the other of the pairs of alined notches 11 and 12. Thus, the edge 71 of the depending lug 70 on the stapling arm 25 is adapted to rock in the arc of a circle about the axis of the pivot-pin 9 and to cooperate with the ledge 18 on the lug 17 of the base 2 to prevent the pivot-pin from being accidentally displaced from the pair of alined notches 11 or 12 in which it is seated. The lug 70 on the arm 25 may be displaced from its cooperative relationship with the ledge 18 on the base 70 2 to permit the arm to be shifted longitudinally of

the base from the position shown in Fig. 1 to that shown in Fig. 2, or vice versa, by rocking the arm through an arc of substantially 45 degrees with respect to the base as illustrated in Fig. 8.

Another novel feature of the present invention 5 consists in the construction and arrangement of the lever 27 to adapt it to cooperate with the abutments or shoulders 19 and 20 on the base 2 to automatically shift the stapling arm 25 from its forward position illustrated in Fig. 2 to its 10 rearward position illustrated in Fig. 1 when the arm is swung through an arc of 180 degrees with respect to the base 2. The rearward portion of the top wall 43 of the lever 27 is so spaced from the axis of the pivot-pin 9 that when the latter 15 is seated in the rearmost pair of alined notches 12 in the stanchions 6 it will clear the shoulder 19 at the end of the lug 17 during rocking movement of the arm 25 with respect to the base to the position illustrated in Fig. 11. However, with the 20 pivot-pin 9 seated in the forward pair of alined notches 11 the rearward portion of the top wall 43 of the lever 27 first engages the shoulder 19 on the lug 17 and subsequently engages the shoulders 20 on the stanchions 6 during the rocking 25 movement of the arm 25 through an arc of 180 degrees with respect to the base whereby to cam the rearward end of the arm downwardly and rearwardly to displace the pivot-pin from the notches 11 and move it into the notches 12, see 30 Figs. 9 and 10. Thus, when the base 2 is rocked away from the arm 25 to adapt the implement to be used as a tacker, the pivot-pin 9 will be seated in the rearward pair of alined notches 12. One preferred form of construction of the invention 35 having been described in detail its mode of operation is explained as follows:

With the parts of the implement in the relationship illustrated in Fig. 1 the magazine 26 is opened to adapt it to receive a supply of staples s 40 by first releasing the latch 55. The latch 55 is slid rearwardly to release its ear 56 from engagement with the shoulder 32 on the magazine 26 and the lever 27 is then swung on the pivot-pin 9 to the position indicated in dash lines in Fig. 12. 45 With the pusher retracted a supply of staples s, preferably in the form of a refill stick is inserted in the magazine 26 between the spaced side walls 29 with the ends of their legs resting against the bottom wall 28. After the magazine 26 has been 50 loaded with a supply of staples s the lever 27 is swung back toward the magazine in the manner indicated by the dotted lines and full lines in Fig. 12. During this movement of the lever 27 the free end of the spring 48 engages the upper edges of 55 the stanchions 6 on the base 2 and the inclined edge 58 of the latch 55 engages the inclined cam-face 15 on the forward edge of one of the stanchions. Further continued movement of the lever 27 toward the base 2 causes the spring 48 to be 60 tensioned and the latch 55 to be slid forwardly by the cam-face 15 until its ear 56 underlies the latching shoulder 32 on the side 29 of the magazine 26.

During this last-explained swinging movement 65 of the lever 27 with respect to the magazine 26 the driver 45 enters the throat 31. When manual pressure on the lever 27 is released the tensioned spring 48, acting against the stanchions 6, causes the lever to move upwardly away from the magazine 26 and base 2 until the ear 56 on the latch 55 engages the latching shoulder 32 on the side of the magazine 26. Thereafter, the magazine 26 will swing upwardly with the lever 27 until the end of the spring 48 is engaged with the top edges 75

of the side walls 29 of the magazine as shown in Fig. 1. Due to the location of the center of weight of the stapling arm 25 forwardly of the point of engagement of the spring 48 with the stanchions 6 on the base 2 the arm tends to rock about the end of the spring as a pivot to maintain the pivot-pin 9 seated in the rearward alined notches 12. To guard against accidental displacement of the pivot-pin 9, however, it is held positively in the alined notches 12 by the cooperation of the depending lug 70 on the magazine 26 with the ledge 18 on the lug 17 of the base 2. If by any chance the rearward end of the stapling arm 25 should be depressed downwardly the lowermost edge 11 of the lug 70 will engage the ledge 18 of the lug 17 to prevent the pivot-pin 9 from being displaced from the notches 12. Due to the clearance between the lowermost edge 11 of the lug 70 and the ledge 18 of the lug 17 the stapling arm may freely rock on the pivot-pin 9 toward and away from the base 2.

The implement may be operated to drive a staple by applying pressure to the forward end of the lever 27 to cause the stapling arm 25 to move toward the base 2 until its forward end is in engagement with the work *w* placed on the anvil 3. Continued pressure on the lever 27 causes the driver 45 to move through the throat 31 to drive a staple therefrom. The pivot-pin 9 being seated in the rearward pair of alined notches 12 positions the driver 45 in alinement with the rearward set of clinching grooves 4 and consequently the legs of the staple will be clinched to form a permanent stitch as illustrated in Fig. 6. When the lever 27 is released the spring 48, acting between the stanchions 6 and the lever, causes the magazine 26 and the lever to be raised to the position illustrated in Fig. 1 in the manner as explained above.

When a temporary pin-stitch is desired the stapling arm 25 is rocked rearwardly through an arc of substantially 45 degrees with respect to the base 2 to the position illustrated in Fig. 8. The depending lug 70 at the rearward end of the magazine 26 will be then displaced above the ledge 18 of the lug 17 on the base 2 to permit the pivot-pin 9 to be disengaged from the alined notches 12 and slid forwardly in the slots 8 to seat it in the notches 11. When the stapling arm 25 is swung downwardly toward the base 2 to the position illustrated in Fig. 2 the depending lug 70 again moves into cooperative relationship with the ledge 18 to prevent the pivot-pin 9 from being accidentally displaced from the alined notches 11. In this last-explained adjustment the driver 45 on the stapling arm 25 is in alinement with the forward set of clinching grooves 5 on the base 2 which are adapted to clinch the legs of the staples to form a temporary stitch as illustrated in Fig. 7. The implement is operated with the stapling arm 25 in this adjusted position in the same manner as explained above by depressing the forward end of the lever 27 to cause the staple-driver to move through the throat 31.

With the stapling arm 25 in either one or the other of its two positions of adjustment the lever 27 may be swung back away from the magazine 26 to either position illustrated in dotted or dash lines in Fig. 12 to open the latter; or the base 2 may be swung back rearwardly of the magazine 26 and lever, considered as a unit, to adapt the implement to be used as a tacker as shown in Fig. 11. With the pivot-pin 9 seated in the alined notches 12 the rearward end of the top wall 43 of the lever 27 will clear the shoulder 19 at the end of the lug 17 and engage the shoulders 20 at

the rear of the stanchion 6 on the base 2 which act as a stop when the base is swung into alined relation to the arm 26, see Fig. 11. However, when the pivot-pin 9 is seated in the alined notches 11 the rearward portion of the top wall 43 of the lever 27 engages the shoulder 19 at the end of the lug 17, as illustrated in dotted lines in Fig. 12. To move the lever 27 to the position illustrated in dash lines in Fig. 12 the magazine 26 is rocked to swing the lug 70 away from the ledge 18 on the base 2. The engagement of the rearward portion of the top wall 43 with the end of the lug 17 then cams the stapling arm 25 downwardly and rearwardly to displace the pivot-pin 9 from the notches 11. Upon continued swinging movement of the lever 27 with respect to the base 2 the rearward edge of the top wall 43 engages the shoulders 20 at the rearward edges of the stanchions 6, see Fig. 10, and cams the pivot-pin 9 rearwardly and upwardly 20 into engagement with the alined notches 12, see Fig. 12. Thus the stapling arm 25 is automatically shifted with respect to the base from its forward position of adjustment to its rearward position of adjustment when the lever is swung 25 through an arc of 180 degrees with respect to the base and the magazine 26 tilted in the manner explained above. The lever 27 is then in position to engage the inclined cam-face 58 at the rear of the latch 55 with the inclined cam-face 15 on the base 2 when the lever is swung back to overlie the magazine.

It will be observed from the foregoing that the present invention provides an implement in which the stapling arm and the base are relatively adjustable to aline the staple-applying means on the arm with different forms of clinching means on the base. It will also be observed that the present invention provides means for holding the stapling arm against accidental displacement from its adjusted position on the base. Still further, it will be observed that the present invention provides for automatically shifting the stapling arm from its forward position to its rearward position of adjustment by rocking the 45 magazine with respect to the base to move its lug away from the ledge and swinging the fastener-applying lever through an arc of 180 degrees into rearward alinement with the base.

While I have shown and described herein a preferred form of construction of the implement, by way of example, it is to be understood that modifications may be made in the structure and arrangement of the parts thereof without departing from spirit or scope of the invention. 55 Therefore, without limiting myself in this respect, I claim:

1. In a device of the type indicated, a base having separate sets of clinching means and a slot with notches therein spaced apart longitudinally thereof, a magazine for fasteners, fastener-applying means movable relatively of the magazine to drive fasteners therefrom, a pivot-pin on the magazine extending through the slot in the base and adapted to seat in the notches 65 to aline the driven fasteners with one or the other of the different sets of clinching means, and a single resilient element for yieldingly holding the magazine raised with respect to the base and biased to retain it in one or the other of its 70 two positions, said element also acting to hold the fastener-applying means raised with respect to the magazine.

2. In a device of the type indicated, a base having spaced sets of clinching means, a maga- 75

- zine for fasteners mounted on the base for movement toward and away from the latter, pin-and-slot means on the base and magazine to adapt the two parts to be moved relatively of each other to aline the driven fasteners with one or the other of the separate sets of clinching means, fastener-applying means movable relatively of the magazine to drive the fasteners therefrom, and a single resilient element for yieldingly holding the magazine raised with respect to the base and biased to retain it in one or the other of its two positions, said element also acting to hold the fastener-applying means raised with respect to the magazine.
3. In a device of the type indicated, a base having spaced sets of clinching means at one end and spaced stanchions adjacent its opposite end, said stanchions having longitudinally-extending slots with pairs of alined notches spaced along their edges, a magazine for fasteners having a throat at one end through which the fasteners are driven and a pivot-pin adjacent its opposite end projecting through the slots in the stanchions, said pivot-pin being adapted to seat in one or the other pair of notches to aline the throat with one or the other set of clinching means, fastener-applying means movable relatively of the magazine to drive fasteners therefrom, and a single resilient element for yieldingly holding the magazine raised with respect to the base and biased to retain the pivot-pin seated in one pair of notches, said element also acting to maintain the fastener-applying means raised with respect to the magazine.
4. In a device of the type indicated, a base having separate sets of clinching means and a slot with notches therein spaced apart longitudinally thereof, fastener-applying means, a pivot-pin on the fastener-applying means extending through the slot in the base and adapted to seat in the notches to aline the driven fasteners with one or the other of the different sets of clinching means, and rigid means on the fastener-applying means and adapted to cooperate with the base for positively holding the pivot-pin in one or the other of the notches to prevent accidental displacement of the fastener-applying means.
5. In a device of the type indicated, a base having separate sets of clinching means and slots with pairs of alined notches spaced apart longitudinally thereof, a fastener-applying arm, a pivot-pin on the arm projecting through the slots in the base and adapted to seat in the alined notches to aline the driven fasteners with one or the other of the different sets of clinching means, and a rigid lug depending from the arm below the pivot-pin and adapted to cooperate with the base for positively holding the pivot-pin in one or the other of the pairs of alined notches to prevent accidental displacement of the arm.
6. In a device of the type indicated, a base having separate sets of clinching means and spaced stanchions projecting upwardly therefrom, said stanchions having slots therein with pairs of alined notches spaced apart longitudinally thereof, a fastener-applying arm, a pivot-pin on the arm projecting through the slots in the stanchions and adapted to seat in the paired notches to aline the fastener-applying arm with one or the other of the separate sets of clinching means, and a rigid lug depending from said arm below the pivot-pin and adapted to cooperate with the base to hold the pivot-pin in one or the other of

the pairs of alined notches, said pivot-pin being releasable to permit it to be slid from one to the other of the pairs of alined notches by rocking the arm away from the base.

7. In a device of the type indicated, a base having separate sets of clinching means and spaced stanchions projecting upwardly therefrom with a ledge between the stanchions, said stanchions having slots therein above the ledge with pairs of alined notches spaced apart longitudinally thereof, a fastener-applying arm, a pivot-pin on the arm projecting through the slots in the stanchions and adapted to seat in the paired notches to aline the fastener-applying arm with one or the other of the separate sets of clinching means, and means on said arm cooperating with the ledge on the base to positively hold the pivot-pin in one or the other of the pairs of alined notches, said pivot-pin being releasable to adapt it to be slid in the slots from one to the other of the pairs of notches by rocking the arm away from the base.

8. In a device of the type indicated, a base having separate sets of clinching means and slots with pairs of alined notches spaced apart longitudinally thereof, a fastener-applying arm, a pivot-pin on the arm projecting through the slots and adapted to seat in the paired notches to aline the fastener-applying arm with one or the other of the separate sets of clinching means on the base, and means on said base engageable with the fastener-applying arm as the latter is swung away from the base to shift the pivot-pin in the slots to engage it with one or the other of the pairs of alined notches.

9. In a device of the type indicated, a base having separate sets of clinching means and slots with pairs of alined notches spaced apart longitudinally thereof, a fastener-applying arm, a pivot-pin on the arm projecting through the slots and adapted to seat in the alined notches to aline the fastener-applying arm with one or the other of separate sets of clinching means on the base, and stepped shoulders on the base below the slots engageable with the rearward end of the fastener-applying arm as the latter is swung away from the base to shift the pivot-pin in the slots from the forward to the rearward set of alined notches.

10. In a device of the type indicated, a base having separate sets of clinching means and spaced stanchions projecting upwardly therefrom, said stanchions having slots therein with pairs of alined notches spaced apart longitudinally thereof, a fastener-applying arm, a pivot-pin on the arm projecting through the slots in the stanchions and adapted to seat in the paired notches to aline the fastener-applying arm with one or the other of the different sets of clinching means, and a lug projecting upwardly and rearwardly from said base and cooperating with the stanchions to provide stepped shoulders, said stepped shoulders on said base being engageable by the rearward end of said fastener-applying arm as the latter is rocked away from the base to cam the pivot-pin downwardly and longitudinally of the slots to shift it from one to another of the pairs of alined notches.

11. In a device of the type indicated, a base having separate sets of clinching means and stanchions projecting upwardly therefrom, said stanchions having slots therein with pairs of alined notches spaced apart longitudinally thereof, a hollow magazine having an open side through which the fasteners are supplied, a lever

for closing the open side of the magazine and having means for driving fasteners from the latter, a pivot-pin connecting the magazine and lever and projecting through the slots in the stanchions, said pivot-pin being adapted to seat in the paired notches to aline the driven fasteners with one or the other of the separate sets of clinching means, and means on the base engage-

able by the end of the lever as the latter is swung with respect to the base, said means on the base being operative to move the pivot-pin downwardly and longitudinally of the slots in the stanchions to shift it from one to another of the pairs of alined notches. 5
